UNITED STATES PATENT OFFICE.

SAMUEL BRAGMAN AND SIGMUND WAGREICH, OF NEW YORK, N. Y.

RECEPTACLE FOR RUBBISH.

1,228,396.

Specification of Letters Patent.

Patented June 5, 1917.

Application filed May 17, 1916. Serial No. 98,101.

To all whom it may concern:

Be it known that we, SAMUEL BRAGMAN, a citizen of Russia, and SIGMUND WAGREICH, a citizen of the United States, both residents 5 of the city of New York, in the county of Bronx and State of New York, have invented a certain new and useful Receptacle for Rubbish, of which the following is a specification.

10 This invention relates to a portable receptacle in which rubbish may be placed.

The object is to make a receptacle with sufficient strength to withstand the rough usage to which it is exposed while moving 15 it about for the purpose of emptying and returning it to its proper place.

The invention consists of a series of metallic hoops which are secured to a series of longitudinal metallic bars, and arranged 20 to produce a stiff cylindrical frame. In this frame are interwoven a series of longitudinal wires and wire hoops, for the purpose of producing a cylindrical cage. Secured to one end of the cylindrical cage is a sheet 25 metal bottom supported by metallic bars, which bars are also secured to the cylindrical frame.

In the accompanying drawing, Figure 1 is a perspective view of the receptacle.

30 Fig. 2 is a sectional plan view, parts being broken away in order to show attachment of the bottom and its supporting frame to the cylindrical cage.

Figs. 3 and 4 are sectional elevations of 35 different parts of the receptacle.

To an upper hoop 1, a lower hoop 2, and a middle hoop 3, each being formed of a flat strip of metal; a series of vertical flat bars 4 are secured by means of rivets 5, 40 thereby producing a cylindrical frame. The portions of bars 4 between the parts attached to hoops 1, 2 and 3, are twisted at right angles to the parts attached, in order that the bars 4 will resist strain in a direction transverse to the cylindrical frame. 45 By reference to Fig. 3, it will be seen that the twist *a* of the bar 4 bears against the edges of hoops 1, 2 and 3, thereby preventing rotational movement of the bars or hoops around the rivets 5. This enables the cylindrical frame to resist torsional strain in line with the hoops, and longitudinal strain in line with the bars 4.

50 Each of the bars 4 is provided with a series of holes 6 through which are passed a series of wire hoops 7. Secured to the

upper hoop 1, are a series of wires 8 which extend downward and are interwoven with the upper wire hoops 7, hoop 3, lower wire hoops 7, and are fastened to the lower 60 hoop 2.

A sheet metal plate 9 provided with a downwardly extending flange 10, is also secured to the lower hoop 2 by means of the rivets 5 and the lower ends of the wires 8. 65

The rivets 5 and wires 8 pass through holes formed in hoop 2 and through holes in downwardly extending flange 10 of plate 9. The plate 9 serves as a bottom for the receptacle. It will be seen that this plate 70 is provided with numerous supports, consisting of the rivets 5 and the lower ends of wires 8. In addition to the supports afforded by rivets 5 and wires 8, the plate 9 is supported by a transverse frame consisting of two bars 11, which are shaped as shown in Fig. 2, and secured together at their centers by means of a rivet 12. The free ends of bars 11 have lateral extensions 75 13, which enable the bars 11 to be secured 80 to the hoop 2 by means of rivets 14.

In addition to supporting the plate 9, the bars 11 serve as transverse braces for the hoop 2. The plate 9 also serves to brace the hoop 2. 85

Having thus described our invention, what we claim is:

1. A receptacle for rubbish comprising a series of flat metallic hoops and a series of flat metallic bars which are fastened together so that a cylindrical frame is produced, parts of each of said bars not attached to said hoops being twisted at right angles to the parts attached; a series of longitudinal wires which are secured to certain 90 of said flat metallic hoops; in combination with a series of wire hoops which are interwoven with said longitudinal wires, and which are passed through a series of holes formed in said parts of said bars which are 95 twisted at right angles to the parts attached to said flat metallic hoops, together with a bottom which is fastened to one of said flat metallic hoops, substantially as described. 100

2. A receptacle for rubbish, comprising a 105 series of flat metallic bars and a series of flat metallic hoops, one of said hoops being secured to one end of each of said bars, another of said hoops being secured to the other end of each of said bars, and a third 110 of said hoops being secured to the middle of each of said bars; parts of each of said bars

not attached to said hoops being twisted at right angles to the parts attached; in combination with a series of wire hoops which are passed through a series of holes formed in said parts of said bars which are twisted at right angles to the parts attached to said flat metallic hoops; and a series of longitudinal wires which are secured to said end hoops and which are interwoven with said wire 10 hoops and said middle flat metallic hoop; together with a bottom which is fastened to one of said end flat metallic hoops, substantially as described.

3. A receptacle for rubbish, comprising a series of flat metallic bars and a series of flat metallic hoops, one of said hoops being secured to one end of each of said bars, another of said hoops being secured to the other end of each of said bars, and a third 20 of said hoops being secured to the middle of each of said bars; parts of each of said bars not attached to said hoops being twisted at right angles to the parts attached; the twist part *a* of said bars by bearing against the edges of said end and middle hoops enabling the cylindrical frame to resist torsional strain in line with the hoops, and longitudinal strain in line with the bars; in combination with a bottom which is fastened to one 25 of said end flat metallic hoops, substantially as described.

4. A receptacle for rubbish, comprising a series of flat metallic hoops and a series of flat metallic bars which are fastened together so that a cylindrical frame is produced; parts of each of said bars not attached to said hoops being twisted at right 35 angles to the parts attached in order that

said bars will resist strain in a direction transverse to the cylindrical frame; the twist part *a* of said bars by bearing against the edges of said hoops enabling the cylindrical frame to resist torsional strain in line with the hoops, and longitudinal strain in line with the bars; a series of longitudinal 40 wires which are secured to certain of said flat metallic hoops; in combination with a series of wire hoops which are interwoven with said longitudinal wires and which are passed through a series of holes formed in said parts of said bars which are twisted at right angles to the parts attached to said flat metallic 45 hoops; together with a bottom which is fastened to one of said flat metallic hoops, substantially as described.

5. A receptacle for rubbish, comprising a series of flat metallic hoops and a series of flat metallic bars which are fastened together so that a cylindrical frame is produced; parts of each of said bars not attached to said hoops being twisted at right angles to the parts attached, in order that 50 said bars will resist strain in a direction transverse to the cylindrical frame; the twist part *a* of said bars, by bearing against the edges of said hoops, enabling the cylindrical frame to resist torsional strain in line with the hoops, and longitudinal strain in line with the bars; in combination with a bottom which is fastened to one of said flat metallic 55 hoops, substantially as described.

Signed at New York city, in the county of New York and State of New York this 16th day of May, A. D. 1916.

SAMUEL BRAGMAN.
SIGMUND WAGREICH.
